COMBINED CONDIMENT DISPENSER SET, HOLDER THEREFOR AND NAPKIN HOLDER

Samuel J. Boker, Brooklyn, N. Y., assignor to Novo-Plas Manufacturing Co., Inc., Brooklyn, N. Y.

Application March 20, 1957, Serial No. 45,370

Term of patent 14 years

(Cl. D44—22)

Fig. 1 is a front elevation of the combined condiment dispenser set, holder therefor and napkin holder, showing my new design;

Fig. 2 is a side elevation thereof seen from the right of Fig. 1; and

Fig. 3 is a rear elevational view thereof, with a napkin shown in broken lines for purposes of illustration.

I claim:

The ornamental design for a combined condiment dispenser set, holder therefor and napkin holder, substantially as shown and described.
